MACHINE FOR INSERTING A DRAWING THREAD OR DRAWING RIBBON IN TAMPOS OR THE LIKE

Friedrich Niepmann and Otto Niepmann, Gevelsberg, Carl Hahn, Köln (Rhine), and Heinz Mittag, Düsseldorf, Germany

Application September 26, 1951, Serial No. 248,332

7 Claims. (Cl. 19—144.5)

This invention relates to a method and machine for inserting a drawing thread or drawing ribbon in tampons or the like. Tampons for women's hygiene are generally provided with a thread or a ribbon which facilitates their removal after use. To provide a tampon with a thread or a ribbon the same may conventionally be sewn together with the wadding or it may be placed about a web of wadding which in turn is rolled about itself.

It is an object of the present invention to provide means for these operations to be carried out automatically. To this end we suggest disposing the thread at a right angle with respect to the wadding web guided through a slot of a winding spindle and to lay it over said spindle by means of two slides or the like, to roll the web and then to press the projecting ends of the thread wound round the spindle against the lower portion of the preformed roll by means of a stripping element or the like. In this way the thread or the ribbon is laid round the wadding web, and after rolling and pressing the tampon the thread is so firmly attached to the tampon that practically it can not be drawn out. The two ends of the thread projecting from the tampon may be knotted together so that the tampon is removed by drawing both ends.

In a machine for carrying out the invention the slides serving to lay the thread over the wadding web may be designed as semi-circular stripping elements which, when the preformed piece is rolled, press the ends of the thread against the lower side of the preformed roll, and which then strip the preformed roll off from the winding spindle. Above the operation way or path of said slides there may be provided guide plates holding and guiding the ends of the thread while being laid over the strip.

On their inner sides the slides are provided with grooves for the thread to be laid in. In like manner, the winding spindle is provided on its front side with a narrow slot for receiving the thread or ribbon, these being thus reliably guided by said slots and grooves when laid over the strip.

Further objects and advantages of the present invention will be apparent from the following description, reference being made to the accompanying drawings wherein a preferred embodiment of the present invention is clearly shown.

Figure 1 is a side view,

Figure 2 is a front view,

Figure 3 is a diagrammatical view showing the thread 60 in its position before the winding spindle,

Figure 4 is a front view of Figure 3,

Figure 5 is a cross section taken on the line V—V of Figure 3,

Figures 6 to 8 show the different positions of the slides 65 when drawing the thread over the spindle.

The wadding web 1 used for the manufacture of a tampon is drawn from a roll 2, passed through two guide rollers 3 and 4, and brought by means of tongs 5 into the position shown in Figure 4. The tongs 5 may be moved and steered in any manner, their operation being not an object of the invention. From the rear side, a winding

2

spindle 6, provided with a slot 7 adapted to receive the strip, is then slid over the strip 1 (Figure 3).

The axial movement to and fro of this spindle 6 is effected by the main shaft 8 of the machine (Figures 1 and 2), which may for example be driven by a gear wheel 9. Mounted on said shaft 8 is a curved drum 10 for the oscillating lever 11 which, through a bushing 12, is so connected to the end of the winding spindle 6 that the latter is capable of rotation.

10 By means of tongs having jaws 13 and 14, the drawing thread 15 or a ribbon serving the same purpose is drawn over a guide roller 16 from a feeding roll (not shown) so as to come to the front side of the winding spindle (Figures 3 and 4). The steering elements of these tongs 15 are shown in Figs. 1 and 2. The jaw 13 is rigidly fixed to a support piece 17 which, by means of a sliding bushing 18, is capable of sliding over a rigidly fixed guide rod 19. The support piece 17 is linked to a rod 20 operated by a lever 21 so as to move up and down. Said lever 21 is mounted on a shaft 22 disposed parallel to the main shaft 8 (Figure 1) and is steered, through a double lever 23 with two rollers 24 and 25, by two curved disks or cams 26 and 27 attached to the main shaft 8. For the sake of clearness said curved disks 26 and 27 are not illustrated in Figure 2 of the drawing.

15 On the support piece 17 of the jaw 13 is mounted the jaw 14 so as to hinge on the bolt 28 (Figure 2). Moreover the support piece 17 carries a short lever 29 which, through two parallel levers 30, is connected to the movable jaw 14, said levers having between them a roller 31. Beside the guide rod 19 there is arranged a movable steering rod 32 having a short travel up and down and being provided with two curved pieces or cam portions 33 and 34 the latter piece being disposed at the upper end 20 of said steering rod 32. At its lower end, said steering rod is rigidly connected to a lifting piece 35 which is guided on the steering rod 19 by means of a bushing 36. The lifting piece 35 engages with a lever 37 which is steered, through the steering lever 38 having rollers 39 and 40, by means of the curved piece or cam 41 mounted on the main shaft 8. The steering lever 38 is mounted on the shaft 42. This steering mechanism is not shown in Figure 1.

25 The tongs operate as follows:

30 In Figure 2 the tongs are in the lowermost position, the roller 31 has run on the curved piece 33 and drawn the jaw 14 from the jaw 13. When the main shaft 8 is set to rotation the whole support piece 17 is lifted through the curved disks 26 and 27, the roller 31 sliding from the curved piece 33 so that the tongs close under the pressure of a spring (not shown). As the support piece 17 approaches its uppermost position the roller 31 runs on the curved piece 34 thus causing the tongs to open again. The drawing thread 15 to be grasped is led through a guide 43 and a bush 44, a short piece of it extending down freely. To ensure that the opened tongs may slide over said free thread end the curved piece 34 is by means of the steering rod 32 lifted a little together with the support piece 17. Such lifting operation is effected by means of the curved disk 41 as described. After reaching the upper limit the support piece 17 is brought down whereas the curved piece 34 remains in its uppermost position so as to enable the tongs to close and to grasp the end of the thread. Near the lower limit the tongs open, and the steering rod 32 is also led down again so that the thread 15 now hangs down vertically before the front side of the winding spindle.

35 Laterally above the winding spindle 6 there is disposed a slide 45 and, below, a slide 46. By means of steering rods 47 and 48, said slides are connected to the end of a double-armed swinging lever 49 which is steered by means of a curved drum 50 mounted on the main shaft 8 (Fig-

ure 1). At the front side of the slides 45 and 46 there are guide pieces 51 and 52, which at their opposite ends are provided with semi-circular cut-outs 53 corresponding to the diameter of the winding spindle 6. On their side directed toward the machine frame, these guide pieces 51 and 52 are provided with narrow key grooves 54 and in the cusp of the cut-outs 53 with grooves 55 (Figure 3).

Above the travel way or path of the slide 45 and below the travel way of the slide 46 there are disposed spring guide plates 56 serving to guide the thread ends as described later. Said guide plates are attached to the vertical part 58 of the machine frame by means of angle pieces 57.

The slides 45 and 46 are connected with bushes 59 capable of sliding on rods 60 and 61. These rods 60, 61 are connected with a pair of levers 62 and 63 which are mounted on shafts 64 and 65 between the machine frame walls 58 and 66. The two levers of each pair of levers 62 are connected with each other by a shaft 67 which engages with the double lever 69 through a steering rod 68. A pivot bearing of said lever 69 is mounted on a shaft 70. The free end of said double lever 69 engages with a rod 71 which is steered by a curved disk or cam 76 through a lever 72, a shaft 73 and another lever 74 with a roller 75. In this way there is achieved a parallel displacement of the two guide pieces 51 and 52 in the direction of the winding spindle 6.

When the slides 45 and 46 and consequently the guide pieces 51 and 52 are in their advanced position (Figure 3), the thread 15 is drawn to come before the winding mechanism. The slides are then moved toward the machine frame after the two knives 77 and 78 have cut off the thread. The guide pieces 51 and 52 now put the thread on the winding spindle 6 which is provided on its front side with a groove 79 for receiving the thread, said groove being made at right angles with respect to the slot 7. When so moved, the thread 15 is caused to lie in the grooves 54 of the guide pieces. During the movement of the slide, the ends of the thread are guided by means of the guide plates 56 as indicated in Figures 6 and 7.

Coincidentally with said horizontal movement of the slides 45 and 46 caused by the curved drum 50, there is another movement of the slides toward the winding spindle 6 which latter movement is caused by the curved disk 76. The semi-circular cut-outs 53 of the guide pieces come nearer and nearer to the winding spindle, the thread being laid into the horizontal grooves 55. When the guide pieces have reached the opposed terminal position (Figure 8), the cut-outs 53 lie on the spindle 6.

The spindle is now driven by means of a gear wheel 81 through a pinion 80 capable of being displaced together with said spindle, the gear wheel 81 in turn being intermittently set to rotation by means of another gear wheel 82 (Figure 1). As a result the wadding web is wound on the spindle to form a preformed roll 83, the thread ends also winding on the spindle (Figure 8). The guide pieces 51 and 52 are then advanced again so that they press the thread ends against the front side of the preformed roll 83, and remove said roll from the spindle to a conveyor band 84 or the like conveying it to a pressing and packing machine.

The method according to the invention above all offers the advantage that the thread or the ribbon is connected to the web mechanically and automatically. The thread ends being as a result of this method disposed on the front side of the tampon may thus be held conveniently when the tampon is to be used.

What we claim is:

1. A machine for inserting a drawing thread or ribbon

in a tampon or the like comprising a winding spindle, a slot provided at one end of said spindle, means for guiding and positioning a wadding web, means for moving said spindle along its axis until the web is received in the slot of said spindle, two slides, means for positioning a thread substantially at right angles to said web and between the web and the initial position of said slides, means for displacing said slides from said initial position along a path substantially parallel to the axis of said spindle until the thread is positioned on said spindle, means for rotating said spindle about its axis to wind a wadding roll of the web, and to wind the free ends of the thread about said spindle, and means for pressing the ends of the thread wound about said spindle against a face of said roll and for simultaneously stripping off said roll and thread from said spindle.

2. A machine as defined in claim 1 comprising semi-circular guide pieces attached to said slides for positioning the thread on said spindle and stripping off said rolls.

3. A machine as defined in claim 2 comprising plates disposed adjacent the path of said slides for guiding the free ends of the thread.

4. A machine as defined in claim 3 wherein the surfaces of said guide pieces facing said spindle are provided with grooves, and wherein a further groove is provided on the end of said spindle facing said thread, said grooves in said guide pieces and in said spindle serving to receive the thread.

5. A machine for providing a tampon or the like with a thread comprising a main shaft, means for rotating said shaft, a curved drum on said shaft, a lever controlled by said drum, a winding spindle, one end of said spindle being coupled to said lever for reciprocating said spindle along its axis upon rotation of said shaft, means for rotating said spindle intermittently about its axis, means for guiding and positioning a wadding web, a slot provided in the other end of said spindle for receiving said wadding web, slides, means for positioning a thread substantially at a right angle to said web and between said web and said slides, means for moving said slides along a path substantially parallel to the axis of said spindle until the thread extends along said spindle, and semi-circular guide pieces attached to said slides for positioning the thread along said spindle.

6. A machine as defined in claim 5 comprising tongs for grasping the thread and pulling it into the path of said spindle, cam means on said shaft, lever means controlled by said cam means and coupled to said tongs for lifting and lowering the same, a guiding rod for guiding said tongs during their lifting and lowering motions, a control rod, cam means carried at the ends of said control rod for opening the tongs held by a spring in the closure position, and means for lifting and lowering said control rod to open said tongs upon displacement of said cam means in response to the movement of said control rod.

7. A machine as defined in claim 6 comprising means for causing said semi-circular guide pieces to approach said spindle as said slides move in an axial direction along said slide to facilitate stripping of said roll.
